UNITED STATES PATENT OFFICE

2,493,863

CREEL

William J. Elvin, Frostburg, Md., and Elmer B. Stahl, Meyersdale, Pa., assignors to Celanese Corporation of America, a corporation of Delaware

Application October 30, 1946, Serial No. 706,746

3 Claims. (Cl. 242—131)

1

This invention relates to textile apparatus wherein filaments, yarn, thread, ribbon, straw and the like (all hereinafter referred to as "yarn") are drawn from one package and wound, with or without twist onto another package support, and relates more particularly to an improved creel arrangement for such textile apparatus.

It is an important object of our invention to provide a novel creel arrangement for yarn winding or twisting and winding apparatus wherein doffing and dressing is substantially facilitated.

Another object of our invention is the provision of a novel creel arrangement for yarn winding or twisting and winding apparatus employing yarn packages having magazine wraps or transfer tails.

A further object of our invention is the provision of a novel creel arrangement for yarn winding or twisting and winding apparatus, which is movable relative to said apparatus for facilitating the doffing and dressing.

Other objects of our invention, together with certain details of construction and combinations of parts, will appear from the following detailed description.

In the drawing wherein a preferred embodiment of our invention is shown,

Figure 1 is a front elevational view, showing the creel of our invention mounted on a conventional down-twister, only a portion of which is shown, and

Figure 2 is a side elevational view thereof, partly in section, showing in broken lines the position of the creel arrangement during the doffing and dressing operation.

Like reference numerals indicate like parts throughout both views of the drawing.

Referring now to the drawing for a detailed description of our invention, reference numeral 3 indicates generally a down-twister to the framework 4 of which is attached a table 5. A series of standards 6, only one of which is shown is supported in brackets, such as bracket 7, fixed to said table 5 at suitable positions along the width of the down-twister. Angle-iron brackets 8 are carried at the upper ends of supports 6. The brackets extend across the width of the down-twister and have fixed thereto, coextensive therewith, bars 9. At suitable stations along the down-twister are positioned arms 11 to which are affixed pigtail guides 12, 13 and 14.

To bars 9 are fixed rails 15 extending at right angles thereto. Carried on rails 15 are slides 16 which are adapted to move horizontally on said

rails 15. The arms 11 are attached to the inner ends of slide 16 and are movable therewith, as shown by dot-dash lines in Fig. 2. Slides 16 are provided at each end with brackets 17 having a bent portion 18. These bent portions carry the means for supporting bobbins 19. The supporting means comprises a circular plate 21 on which the bottom of the yarn package is adapted to rest, a space 22 on said plate, a plate 23 of smaller diameter, a spacer 24, and a plate 25 of a still smaller diameter, all held together by means of a bolt 26, extending through the plates, spacers and bent portions 18, and nuts 27. The diameters of plates 23 and 25 are such as to fit snugly within the skirt 28 of the bobbin 19.

The bent portions 18 of brackets 17 are inclined so that the yarn packages supported thereon are inclined toward each other. The inclination of the yarn packages permits of easy withdrawal of the yarn over the top.

In operation, two yarn packages are mounted on each creel in alignment with each other and the leading end of one yarn package is tied to the transfer magazine wrap or tail of the other package. The leading end of the latter package is threaded through guides 14, 13 and 12, then through guide eye 29, is passed over steel feed roll 31, wrapped around cork covered nip roll 32, and finally taken up on any suitable means (not shown). The feed rolls 31 and nip rolls 32 are mounted on shafts 33 and 34, respectively. As shown in dot-dash lines in Figure 2, when the yarn on the bobbin has become exhausted, the operative pulls the slide 16 forward until it is halted by stop pin 35. The exhausted bobbin is replaced by a full bobbin and the leading end of the yarn thereof is tied to the magazine wrap or transfer tail of the unexhausted bobbin, after which the slide and the bobbins are slid back to their original or operating position. The operation of the down-twister is not halted during the doffing and dressing operations above described.

It is to be understood that the foregoing detailed description is given merely by way of illustration and that many variations may be made therein without departing from the spirit of our invention.

Having described our invention, what we desire to secure by Letters Patent is:

50 1. A creel for winding or twisting textile machines having a bar extending transversely thereof, said creel comprising a rail having one end attached to said bar, a slide telescopically carried by said rail for movement relative thereto, an arm, having a yarn guide thereon, and brackets

fixed to said slide and means carried by said brackets for supporting a yarn package thereon.

2. A creel for winding or twisting textile machines having a bar extending transversely thereof, said creel comprising a rail having one end attached to said bar, a slide telescopically carried by said rail for movement relative thereto, an arm, having a yarn guide thereon, fixed to one end of said slide and a bracket fixed to each end of said slide and means carried by said brackets 10 for supporting a yarn package thereon.

3. A creel for winding or twisting textile machines having a bar extending transversely thereof, said creel comprising a rail having one end attached to said bar, a slide telescopically 15 carried by said rail for movement relative thereto, an arm, having a yarn guide thereon, fixed to one end of said slide and a bracket, having a bent portion, fixed to each end of said slide and means

carried by said bent portions of said brackets for supporting a yarn package thereon, said bent portions being inclined so as to cause the packages supported thereon to be inclined towards each other.

WILLIAM J. ELVIN.
